(57) **CLAIM**

The ornamental design for a double pin stripe solar module article, as shown and described.

DESCRIPTION

FIG. 1 is a perspective view of a double pin stripe solar module article showing our new design; FIG. 2 is a front elevation view thereof; FIG. 3 is a rear elevation view thereof; FIG. 4 is a top plan view thereof; FIG. 5 is a bottom plan view thereof; FIG. 6 is a side elevation view thereof; FIG. 7 is another side elevation view thereof; and, FIG. 8 is an enlarged view of area 8 of FIG. 2 thereof. The broken line in the figure drawings is included for the purpose of illustrating unclaimed environment and forms no part of the claimed design.
